(57) **CLAIM**

The ornamental design for a bottle as shown and described.

DESCRIPTION

FIG. 1 is a perspective view of a bottle, showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the bottle showing an environmental bottle cap on the bottle.

Broken lines seen depicting the bottle cap in FIG. 9 depict environmental subject matter and form no part of the claimed design. All other broken lines seen in the drawings depict portions of the bottle that form no part of the claimed design.
